UNITED STATES PATENT OFFICE.

PETER WEBER, OF CHEYENNE, WYOMING.

ADJUSTABLE STAND.

Application filed March 23, 1927. Serial No. 177,807.

This invention relates to adjustable stands and more particularly to stands for holding a rivet cutter during the cutting of rivets on a steel railroad car and similar work.

5 A primary object of the invention is to provide means for relieving the operator, when riveting, avoiding the necessity of holding the rivet cutter continuously and which provides for the easy and reliable performance of the work, and avoids breakage of the chisel in the cutter, which frequently occurs when the cutter is manually held.

10 Another object is to provide a stand of this character which enables a rivet to be cut on top at a much higher elevation than can be done when the cutter is held by hand, and which permits a rivet to be much more easily cut from underneath, because of the fact that the operator can hold the chisel to the rivet, 15 the holder for the cutter being adjustable at any desired height.

Another object is to provide a device of this character equipped with means for holding the chisel at a proper angle for cutting.

20 Still another object is to so construct a stand of this character that it may be held rigidly by means of the operator standing on a platform provided for this purpose.

In carrying out these objects, the invention 25 is susceptible of modification without departing from the spirit or sacrificing any of the advantages of the claimed invention; there being shown in the drawings for illustrative purposes, a preferred and practical form, in 30 which:

Figure 1 represents a perspective view of this improved stand shown in position ready for use,

Fig. 2 is a front elevation thereof with the 35 platform shown in transverse section, and

Fig. 3 is an end elevation thereof, parts being broken off for convenience in illustration.

In the embodiment illustrated the stand 40 constituting this invention comprises four legs numbered 1 and which taper in width from their upper toward their lower ends and which may be constructed of any suitable material, preferably of wood. Transverse tie 45 bars 2 connect the legs at the ends of the stand intermediate their length, and a longitudinally disposed board or bar 3 is fixedly secured to the tie bars 2 for rigidly holding the members of the stand together. This bar 50 3 projects at its ends beyond the end tie bars 2 and is slotted as shown at 4 for the passage

therethrough of rack bars 20 and forms a guide for said bars. It will thus be seen that this member 3 performs a double function of a tie bar and a rack bar guide.

60

A plurality of spaced longitudinally extending bars 5 connect the legs 1 at the ends of the stand and are designed to strengthen and rigidify the stand in addition to forming means for supporting one end of a platform 30 and as supports for the rivet cutter as will be presently more fully described. Four of these bars 5 are shown although obviously any desired number may be used. Arranged above this group of bars 5 is 65 another bar 6 to support the rivet cutter.

The top 7 of this stand is fixed to the converging upper ends of the pairs of end legs 1 and is composed of three boards or sections 8, 9 and 10, bolted together and to the legs 1. 70

Mounted on the top 7 is an auxiliary top 11 also composed of three boards or sections 12, 13, 14, the central or intermediate member of both of these tops being preferably made of hard wood. This top 11 is connected with 75 the ratchet bars or levers 20 which are equipped on their inner edges or faces with a plurality of spaced ratchet teeth or recesses 21 designed to engage the ends of the member 9 which terminates short of the members 8 and 10, the projecting ends of the latter having bolts 7^a extending through them and spanning the space between them and in which space the bars 20 operate. By making this member 11 adjustable in the manner above 80 described, the rivet cutter resting thereon may have the cutter proper positioned at any desired angle to adapt it to properly engage the rivet to be cut.

85 From the above description, it will be seen that the rivet cutter may be used by resting it on the tops of bars 5, or on bar 6, or on either of tops 7 or 11, and as above described, the top 11 may be adjusted to support the cutter at an elevated position above the stand 90 proper.

95 The platform 30 has one end reduced as shown at 31 and at the junction of said reduced portion with the body 2 of the platform has transversely arranged cleats 33 and 34 secured to the upper and lower faces thereof and which project beyond the ends of the reduced portion 31 and form shoulders or abutments to engage the legs 1 at opposite ends of the stand to limit insertion of the extension 100 31 between two of the bars 5, said cleats being 105 designed to abut said bars to facilitate mount-

ing of the platform on the stand. At the outer end of this platform 30 are legs 35 which are designed to support the platform at this point. This platform is designed as 5 a support for the operator who in turn by his weight holds the stand in rigid position preventing all danger of its tipping or tilting while the rivet cutter is in operation.

A lock for the extension member 11 is provided 10 in the form of a keeper 22 mounted on one end leg 1 as shown in Fig. 3, which is designed to receive a latch 23 pivoted at one end to the other end leg. This latch when 15 swung into operative position spans the space between the two end legs and holds the member 20 with one of its notches or teeth 21 engaged with the bar 9 of top 7 and thus securely locks the extension in adjusted position. To release the members 20 for the 20 adjustment of the extension the latch is swung 25 out of engagement with the keeper 22 and these members 20 owing to their slotted connection with the members 12 and 14 of top 11 and with board 3 may be swung out to disengage the notches 21 from bar 9 and thus permit top 11 to be raised or lowered, as desired. This slotted connection of members 20 with the top 11 also provides a pivotal connection 30 at these points so that one of the members 20 may be raised or lowered independently of the other to vary the angle or inclination of the member 11 when it is desired to support the rivet cutter at such an angle.

From the above description it will be seen 35 that this stand is exceptionally well adapted to form a rest or support for a rivet cutter while cutting rivets on a steel railroad car or any other similar work, it being well known that such cutters are heavy cumbersome 40 some tools and which, when held manually, quickly tire the operator and prevent him from accomplishing the cutting operation in the most skilled manner. The mounting of the rivet cutter on a stand provides for the 45 steady holding of the chisel and thereby prevents danger of breaking it.

Without further description it is thought 50 that the features and advantages of the invention will be readily apparent to those skilled in the art, and it will of course be understood from changes in the form, proportion and minor details of construction may be resorted to, without departing from the spirit of the invention or its scope as claimed.

55 I claim:—

1. A holder for rivet cutters and the like comprising a stand having a plurality of cutter rests and means pivotally connected with one of said rests for adjusting it vertically at an angle to vary the cutting angle of the tool mounted thereon.

60 2. A holder for rivet cutters and the like

comprising a stand including pairs of connected end legs, those of each pair diverging from their upper toward their lower ends, top 65 bars connecting the upper ends of said legs and spaced transversely from each other with the ends thereof extending beyond the outer edges of the legs, transverse members connecting said extended ends to provide a space 70 between them and the legs, an auxiliary top mounted on said main top and movable vertically relatively thereto, pivoted levers depending from said auxiliary top and extending through the spaces between the transverse 75 members and the legs, said levers being provided on their inner edges with spaced ratchet notches, a plate extending longitudinally of said stand between the legs thereof and having longitudinally extending openings in their ends through which said levers extend and are guided, said openings being larger than the legs to permit the free swinging movement of said levers to provide for the engagement of the ratchet notches with 80 the walls of the inner ends of said openings whereby the auxiliary top is held in adjusted 85 position, and means for locking said levers engaged with said plate.

3. A holder for rivet cutters and the like 90 comprising a stand including pairs of connected end legs, those of each pair diverging from their upper toward their lower ends, top bars connecting the upper ends of said legs and spaced transversely from each other 95 with the ends thereof extending beyond the outer edges of the legs, transverse members connecting said extended ends to provide a space between them and the legs, an auxiliary top mounted on said main top and movable vertically relatively thereto, pivoted levers depending from said auxiliary top and extending through the spaces between the transverse members and the legs, said levers being provided on their inner edges with 100 spaced ratchet notches, a plate extending longitudinally of said stand between the legs thereof and having longitudinally extending 105 openings in their ends through which said levers extend and are guided, said openings being larger than the legs to permit the free swinging movement of said levers to provide for the engagement of the ratchet notches with the walls of the inner ends of 110 said openings whereby the auxiliary top is held in adjusted position, and a latch member pivoted on one of the legs of one pair and adapted to swing across the outer face of the cooperating lever and means carried by the other leg of the pair for engagement with 115 said latch to hold the lever in adjusted position.

PETER WEBER.
